UNITED STATES PATENT OFFICE.

RUBEN W. SMEDBERG, OF ST. PETER, MINNESOTA.

ELECTRICALLY-ACTUATED CLOCK.

No. 846,515.

Specification of Letters Patent.

Patented March 12, 1907.

Application filed July 9, 1906. Serial No. 325,303.

To all whom it may concern:

Be it known that I, RUBEN W. SMEDBERG, a citizen of the United States, residing at St. Peter, in the county of Nicollet and State of Minnesota, have invented certain new and useful Improvements in Electrically-Actuated Clocks; and I do hereby declare the following to be a full, clear, and exact description of the invention, such as will enable others skilled in the art to which it appertains to make and use the same.

My invention relates to electrically-actuated clock systems wherein clocks at the different stations are automatically actuated by electrical impulses sent out at predetermined intervals from the central or controlling station, such impulses being controlled by a central or regulating clock.

The invention has for its object to provide an improved clock for use at the different stations; and to this end it consists of the novel devices and combinations of devices hereinafter described, and defined in the claims.

The improved clock is illustrated in the accompanying drawings, wherein like characters indicate like parts throughout the several views.

Referring to the drawings, Figure 1 shows the clock in rear elevation with some parts broken away and with some parts removed, and Fig. 2 shows the said clock in side elevation.

The numeral 1 indicates a suitable clock-frame on which the running parts of the clock are mounted. Mounted centrally in the frame 1 is a rotary spindle 2, that carries the minute-hand 3. The hour-hand 4 is loosely mounted on the outer end of the shaft 2 and is connected by a sleeve to a spur-gear 9, that is also loosely mounted on said shaft. The gear 9 meshes with a spur-pinion 8, that is carried by a counter-shaft 7, also journaled in the frame 1. The shaft 7 carries a spur-gear 6, that meshes with a spur-pinion 5, which in turn is rigidly secured to the shaft 2. The dimensions of the gears 6 and 9 and pinions 5 and 8 are such that the minute-hand 3 will be given twelve rotations for each rotation of the hour-hand 4.

The shaft 2 at its intermediate portion carries a large spur-gear 10, that meshes with a small pinion-gear or lantern-wheel 11, that is secured to a spindle 11^a, journaled in the sides of the frame 1. The spindle 11^a also carries a large ratchet-wheel 13. The rela-

tive size of the wheels 10 and 11 is such that twelve rotations of the latter are required to impart one rotation to the former and to the shaft 2 and minute-hand 3. As shown and preferred, the ratchet-wheel 13 is provided with one hundred and fifty teeth.

The teeth of the ratchet-wheel 13 are engaged by a pair of alternately-acting spring driving-pawl 14 and 15, that are secured to the opposite ends of a vibratory head 16, which head is secured to a rock-shaft 17, mounted on the frame 1. This rock-shaft 17 has a projecting arm 18, that carries an armature 19, which armature is subject to a pair of wound magnets 20, shown as supported by the frame 1. The coils of the magnet 20 are connected by wires 21 in circuit with a suitable source of electrical energy, such as a battery or dynamo at a central station, and suitable means (not shown) may be provided for producing pulsations in circuit or for intermittently making and breaking the circuit at the central station. Means for making and breaking the circuit at the central station would be actuated by the pendulum of the central or controlling clock, and the said circuit should be closed and opened once each two seconds of time—that is, the circuit will be closed one second and opened the next, and vice versa.

The two spring-pawl 14 and 15 press laterally against the ratchet-wheel 13, and hence tend to raise the armature 19 against the fixed stop 22 on the frame 1. When the magnet-circuit is broken, by reference to Fig. 2 it will be seen that normally the pawl 15 stands on the intermediate portion of one of the teeth of the ratchet-wheel. With this construction when the armature 19 is drawn downward the pawl 14 will impart a step of rotary movement to the ratchet-wheel 13 approximately equal to one-half a tooth of distance and the said pawl 15 will be drawn down into engagement with the next lower tooth. When the magnet-circuit is broken and the armature 19 is moved upward, said pawl 15 will impart a second half-step or half-tooth of movement to said ratchet-wheel 13 and the pawl 14 will be drawn downward into engagement with the next lower tooth. It is thus evident that a complete upward-and-downward movement of the armature 19 is required to impart to the said ratchet-wheel a movement which represents one tooth thereof and which in time represents two seconds or two seconds of

movement of the minute-hand 3. With the ratchet-wheel 13 provided with one hundred and fifty teeth the said ratchet-wheel will be given one complete rotation every five minutes, the minute-hand 3 will be given one complete rotation each sixty minutes, or one hour, and the hour-hand will be given one complete rotation every twelve hours. With this arrangement, whereby the ratchet-wheel 13 is given one step of movement for each second of time, the application of a seconds-hand to the clock is an easy matter. As is obvious, such seconds-hand may be driven by any suitable means from the said ratchet-wheel.

The improved clock above described, while extremely simple and of small cost, is thought to be highly efficient for the purposes had in view. It is of course evident that any number of these clocks located at various different points may be operated by a single controlling-clock at the central station regardless of the distance between said several clocks and the controlling-station.

With the construction above described it is evident that the magnet acting through the armature and the pawls that are vibrated thereby serves to impart positive step-by-step rotary movements to the ratchet-wheel and parts driven thereby and that each movement of said armature produces a movement of the ratchet-wheel 13 representing one-half tooth, or one second of time.

What I claim is—

1. In an electrically-actuated clock, the combination with the minute and hour hands and gears connecting the same for properly - timed movements, of a ratchet-wheel for driving said gears, a magnet in an actuating-circuit, a vibratory armature subject to said magnet, and a pair of reversely-acting spring - pressed pawls connected to and receiving reversely vibratory movements

from said armature, and which pawls are pressed laterally against said ratchet-wheel 45 and serve to retract said armature from said magnet when the actuating-circuit is broken, substantially as described.

2. In an electrically-actuated clock, the combination with the minute and hour hands and gears connecting the same for properly-timed movements, of a ratchet-wheel for driving said gears, a magnet in an actuating-circuit, a pivoted arm having an armature subject to said magnet, a head connected to 55 said arm, and a pair of reversely-acting spring-pawls secured to said head and operating on said ratchet-wheel, and which spring - pawls press laterally against said ratchet-wheel and serve to retract said armature 60 from said magnet when the circuit is broken, substantially as described.

3. In an electrically-actuated clock, the combination with the minute and hour hands and gears connecting the same for properly-timed movements, of a ratchet-wheel for driving said gears provided with one hundred and fifty teeth, a magnet in an actuating-circuit, a pivoted arm having an armature subject to said magnet, a pair of reversely-acting 70 spring-pawls carried by said arm and pressing laterally against the teeth of said ratchet-wheel with a force tending to retract said armature from said magnet, and which spring-pawls under one movement of said armature 75 impart a first half-step of movement to said ratchet-wheel, and under the other movement of said armature impart a second half-step of movement to said ratchet-wheel, substantially as described.

In testimony whereof I affix my signature in presence of two witnesses.

RUBEN W. SMEDBERG.
